UNITED STATES PATENT OFFICE.

HARRY H. GOODALL, OF TOLEDO, OHIO.

DESIGN FOR AN AUTOMOBILE-BODY.

54,549.

Specification for Design.

Patented Mar. 2, 1920.

Application filed October 13, 1917. Serial No. 196,516. Term of patent 14 years.

To all whom it may concern:

Be it known that I, HARRY H. GOODALL, a citizen of the United States, residing at Toledo, in the county of Lucas and State of Ohio, have invented a new, original, and ornamental Design for Automobile-Bodies, of which the following is a specification, reference being had to the accompanying drawing, forming a part thereof.

The drawing is a perspective view of an automobile body showing my new design.

What I claim is:

The ornamental design for an automobile body as shown.

In testimony whereof I affix my signature.

HARRY H. GOODALL.
